DESIGN FOR A CONCRETE VIBRATOR OR THE LIKE

Arthur William Mall, Flossmoor, Ill.

Application March 15, 1940, Serial No. 90,936

Term of patent 3½ years

To whom it may concern:

Be it known that I, Arthur William Mall, a citizen of United States, residing at Flossmoor, in the county of Cook and State of Illinois, have invented a new, original, and ornamental Design for a Concrete Vibrator or the like, of which the following is a specification, reference being had to the accompanying drawing, forming a part thereof, in which:

Fig. 1 is a side elevational view of a concrete vibrator or the like showing my new design; and

Fig. 2 is an elevational view of the same concrete vibrator or the like taken at right angles of Fig. 1.

I claim:

The ornamental design for a concrete vibrator or the like, substantially as shown.

ARTHUR WILLIAM MALL.
